Inventor,

Warren S. Bellows;

By *A. Blpham*,
Attorney.

UNITED STATES PATENT OFFICE.

WARREN S. BELLows, OF WORCESTER, MASSACHUSETTS.

WRENCH-SOCKET.

1,282,028.

Specification of Letters Patent. Patented Oct. 22, 1918.

Application filed January 28, 1916. Serial No. 74,953.

To all whom it may concern:

Be it known that I, WARREN S. BELLows, a citizen of the United States, and a resident of Worcester, in the county of Worcester 5 and Commonwealth of Massachusetts, have invented certain new and useful Improvements in Wrench-Sockets, of which the following is a full, clear, and exact specification.

15 This invention relates to an improved means for enabling metal rods to be attached to sockets for the economical and efficient manufacture of wrenches, and formed a part of my patent application which eventuated 15 in U. S. Letters Patent No. 1,167,542, granted January 11, 1916.

In the drawings forming part of this specification, Figure 1 is a side view of a length 20 of metal rod bent to compose a handle and a shank, and having my socket connected therewith. Fig. 2 is a side view of a length 25 of metal rod bent for the same purpose but in a different manner, showing the socket in section. Fig. 3 is a longitudinal section of 30 the socket alone. Fig. 4 is an end view of the socket. Fig. 5 is an end view of the same but from the opposite direction. Fig. 6 is a perspective view of the end portion of a length of metal rod shaped for attachment 35 in the socket.

The socket member 1 consists of a forging 40 or casting having a socket 2 in its lower end, and an axially disposed hole 3 opening from said socket through to the upper end of said member. As illustrated in Fig. 4, the socket 45 is hexagonal, but it is evident that the same may be of any desired shape and size to fit the kind of bolts and nuts for which the wrench may be used. As shown in Figs. 4 and 5, said hole 3 is not cylindrical, but the upper section thereof is made with two parallel flat surfaces 4, 5, and two limited cylindrical surfaces 6, the object of which is hereinafter set forth. The lower section of said 50 hole is larger than said upper section, tapering into each other, as shown in Figs. 3 and 4.

The handle and shank of this wrench consist of a single length of metal rod bent to form a shank 7 and cross handle 9. In 55 forming said parts, the rod is first bent nearly at right angles, as at 10, and then over on itself at 11, so that the cross handle 9 is disposed at right angles to the shank, with the latter at the midlength of the handle, the shank and handle being rigidly

united by the connecting section 13. This construction is illustrated in Fig. 1, and while it forms a most practical arrangement, it is still further improved upon by prolonging the handle and bending over 60 upon it the prolongation 14, as shown in Fig. 2. This prolongation terminates at the intersection of the handle and shank.

To fasten the shank within the socket member 1, the former has two opposite portions of its surface milled away to fit between the surfaces 4 and 5, while the diameter of the shank is the same as that of the curved surfaces 6. Fig. 6 shows the milled portions. After such milled section has been 70 introduced into the hole 3, the end of said section is hammered until the metal has been forced laterally to practically the tapered section 8, as illustrated in Fig. 2, the shoulders 12 immediately above said milled portions 75 serving to keep the socket member from slipping upward on the shank.

This not only locks the shank from withdrawal from the socket, but, said section 8 being also flattened, as shown in Fig. 4, the 80 forcible turning of the socket with the handle is perfectly insured.

It will be observed that upon expanding the end of the shank, the metal is forced 85 against the inclined walls of the opening in the socket, and at the same time the socket is forced into tight engagement with the shoulders on the shank, thus positively preventing any possible looseness or wabbling 90 of the socket on the shank. The construction illustrated enables the use of a round wire handle or shank, and the effective securing thereon of the socket with a minimum amount of milling and fitting. The inclined flat walls of the opening in the 95 socket afford a large area of bearing and holding surface, which would not be present with the ordinary heading or upsetting of the end of the shank. With this construction, it is apparent that the connection between the shank and socket must become 100 loose on the whole length of the inclined walls before any relative movement of the socket and shank can take place.

What I claim is:

1. A wrench comprising a socket formed on one side thereof with a recess to fit a nut or bolt head and in the opposite end thereof with an irregular shaped opening extending into said recess, the walls of said opening 110

- diverging toward the base of the recess and a shank provided with a reduced end having a cross section corresponding substantially with the irregular shaped opening, and 5 adapted to fit therein, the extremity of said reduced portion of the shank being expanded into snug engagement with the walls of the irregular shaped opening in the socket.
- 10 2. A wrench comprising a socket formed in one end thereof with a polygonal recess adapted to receive a nut or bolt, and in the opposite end thereof with flat sided opening extending into said recess, the walls of 15 said opening diverging inwardly to the base of the polygonal recess, and a shank having one end thereof also flat sided to fit thereto and interlock therewith, the said shank being provided with shoulders above the 20 flat sided opening, and the extremity of said flat sided end of the shank being upset to force the same into a snug engagement with the diverging walls of the flat sided opening and to force the socket tightly against 25 the shoulders on the shank.
3. A wrench comprising a socket member provided in one end thereof with a polygonal recess adapted to receive a nut or bolt head, and in the opposite end thereof with 30 an opening extending into the polygonal
- recess, the said opening being formed with a pair of opposed flat walls connected at their sides by a pair of opposed curved walls each of which is an arc of a circle, said flat walls diverging inwardly to the base of the 35 polygonal recess of the socket, and a shank formed of a metallic rod having a circular cross section of a radius substantially equal to the radius of the curved walls of the opening in the socket, one end of said rod 40 being provided with a pair of opposed flat faces corresponding with the flat walls of the opening in the socket, said flat faces terminating at their inner ends in square shoulders, said flat faces and shoulders 45 being formed by milling away portions of the rod, the said end of the shank being adapted to snugly fit within the opening in the socket and the extremity thereof being upset to force the same into tight engagement with the flat walls of the opening and to force the socket tightly against the said shoulders on the shank.
- In testimony that I claim the foregoing invention, I have hereunto set my hand this 50 25th day of January, 1916.
- WARREN S. BELLows.
